UNITED STATES PATENT OFFICE.

JAMES H. RAY, OF HIGGINS, TEXAS.

SILO.

1,118,231.

Specification of Letters Patent. Patented Nov. 24, 1914.

Application filed June 12, 1914. Serial No. 344,763.

To all whom it may concern:

Be it known that I, JAMES H. RAY, a citizen of the United States, residing at Higgins, in the county of Lipscomb and State of Texas, have invented certain new and useful Improvements in Silos, of which the following is a specification.

This invention relates to improvements in silos.

10 The primary object of the invention is the provision of a silo which is constructed from cement or other like material and which is provided with suitable reinforcing means.

15 A further object of this invention is the provision of a silo having a novelty constructed and reinforcing doorway designed to provide a ladder by means of which a person may obtain access to the upper end of the said silo.

20 A further object of the invention is the provision of a reinforced cement silo provided with spaced rods disposed upon opposite sides of the doorway and horizontal spaced rings embedded in said silo for the 25 purpose of reinforcing the same and having rungs extending across the doorway to produce a ladder, the alternate of the rungs being extended forwardly through the side of the silo and constituting attaching means 30 for engagement with a chute or other means whereby the contents of the silo may be discharged.

25 A still further object of this invention is to improve and simplify devices of this 35 character rendering them comparatively simple and inexpensive to manufacture, reliable and efficient in use and readily accessible.

With the above and other objects in view, 40 the present invention resides in the novel features of construction, formation, combination and arrangement of parts to be hereinafter more particularly described, claimed and illustrated in the drawing in 45 which the figure is a perspective view of my invention.

Referring to the drawing by similar characters of reference through the several views, the numeral 5 designates generally 50 my improved silo which is preferably of cylindrical formation and constructed either of cement or other like substance, the same being provided with the usual doorway 6 recessed at its inner side as at 7 for engagement with the removably sliding door panels 8. The opposite sides of the doorway 6 are

reinforced by the vertical rods 9 which are embedded in the material of the silo adjacent the opposite sides of said doorway. A plurality of horizontal spaced rings 10 are likewise embedded in the material of the silo, completely encircling the latter within the walls thereof. The inner ends of these rings 10 are bent as at 11, to embrace the vertical reinforcing rods 9. The opposite sides of the rings 10 are connected by a strand of wire 12 which is attached to the said rings 10 as shown at 13. The reinforcing rods 9 are connected by equi-spaced main rungs 14 and intermediate rungs 15 which extend across the doorway as clearly shown in the drawing, forming a ladder by means of which a person may obtain access to the upper end of the silo for any purpose. The ends of these rungs 14 and 15 embrace the reinforcing rods 9 as shown by the numerals 16, while the terminals of the rungs 15, which are disposed between the rungs 14, are extended forwardly through the side of the silo, providing parallel supporting arms 17, formed with terminal eyes 18 by means of which a suitable chute (not shown in the drawing) may be attached to the silo at any desired height for the purpose of assisting in the removal of the contents of the silo.

From the foregoing disclosures it will be manifest that a silo is provided which will fulfil all the necessary requirements of such a device. It should also be understood in this connection that various minor changes in the specific details of construction can be resorted to within the scope of the appended claims without departing from or sacrificing any of the advantages of the invention.

What is claimed is:

1. In a silo such as described, a cylindrical body portion formed of plastic material, said silo having a doorway formed in one side thereof, spaced vertical reinforcing rods embedded in the body of said silo upon opposite sides of the doorway, rings embedded in the material of the silo and encircling the same, said rings having their opposite ends connected to the vertical reinforcing rods, rungs connecting said vertical reinforcing rods and extending across said doorway, each alternate rung engaging the vertical reinforcing rods and contacting with the ends of the rungs, said alternate rungs having forwardly extending arms projecting through one side of the silo, ter-

minal eyes provided upon said arms and a strand connecting said rings upon the side of the silo opposite to the doorway.

2. In a silo, a body portion having a doorway formed therein, vertical reinforcing rods disposed upon opposite sides of the doorway, rings connected to said reinforcing rods and embedded in the silo, a strand of wire connecting said rings, main rungs connecting the reinforcing rods intermediate the rings and extending across said doorway, and intermediate rungs connecting the reinforcing rods and contacting with the ends

of the rings, and forwardly extending arms extending from the ends of the intermediate rungs and projecting through the side of the silo upon opposite sides of the doorway, said arms having eyes provided therein for the purposes set forth.

In testimony whereof he affixes his signature in presence of two witnesses.

JAMES H. RAY.
